UNITED STATES PATENT OFFICE.

PETER WILLIAMS, OF INGALLSTON, MICHIGAN.

DESIGN FOR A WEAPON.

48,510.

Specification for Design.

Patented Feb. 1, 1916.

Application filed November 6, 1915. Serial No. 60,146. Term of patent 7 years.

To all whom it may concern:

Be it known that I, PETER WILLIAMS, a subject of the Czar of Russia, residing at Ingallston, in the county of Menominee and State of Michigan, have invented a new, original, and ornamental Design for a Weapon, of which the following is a specification, reference being had to the accompanying drawing, forming part thereof.

The figure is a view in perspective of a weapon, showing my new design.

I claim:—

The ornamental design for a weapon, as shown.

PETER WILLIAMS.

Witnesses:

FLORENCE FRANK,
JACOB J. MARTINEK.
